UNITED STATES PATENT OFFICE.

JAMES J. WOOD, OF BROOKLYN, ASSIGNOR TO THE FULLER ELECTRICAL COMPANY, OF NEW YORK, N. Y.

ELECTRIC LAMP.

SPECIFICATION forming part of Letters Patent No. 279,472, dated June 12, 1883.

Application filed July 15, 1881. (No model.)

To all whom it may concern:

Be it known that I, JAMES J. WOOD, of Brooklyn, Kings county, New York, assignor to the FULLER ELECTRICAL COMPANY, of New York city, have invented certain new and useful Improvements in Electric Lamps, of which the following is a specification.

My present invention relates to that class of arc-lamps known as "double" or "duplex," which are provided with two or more sets of carbons and corresponding holders, the second or succeeding set of which becomes thrown into luminous action as soon as the first set is exhausted, whereby the light of the lamp is continued without interruption or attendance over a longer period. The aim of my present improvement is to provide a simple and efficient lamp of this character, which will embody two or more sets of carbons in such a way that one set only will be in action at the same time and the strain of one only borne by the regulating mechanism and its magnets or other motor, so that such mechanism and motor shall have only the same work to perform as it has in an ordinary single lamp, and will require no increase in dimensions, power, or consumption of current, as is the case with some duplex lamps heretofore produced, in which the strain of both carbons is constantly borne by the magnet and both are moved at the same time, but the one slightly in advance of the other. In my lamp both electrodes or carbon-holders are constantly connected with the regulating mechanism by distinct ratchet or equivalent clutches having the same direction of action and slip, so that, if one electrode be simply supported independently of the mechanism and the other borne by the mechanism, the mechanism will move or actuate only the borne one without ever becoming disconnected from either, and by causing the leading and borne electrode at its terminal motion to simply remove its pressure from mechanism and transfer the pressure of the succeeding electrode thereto, the mechanism immediately ceases to actuate the relieved and exhausted electrode and at once controls the second electrode; and my invention con-

sists, mainly, in the organization here outlined, as hereinafter fully set forth. The mechanism of my invention which accomplishes this result, while being very simple and efficient, is yet of that kind whose action is somewhat involved and is not immediately perceived, and does not admit of entire elucidation in a brief description; but in the full illustrations and description which follow the same will be fully elucidated.

In the annexed drawings, Figure 1 gives a front elevation of my improved duplex lamp, the view being a general external one, on a small scale, as the lamp appears ready for use, the head or frame containing the mechanism being covered by its cylindrical case, which conceals and protects the mechanism. Fig. 2 is a side elevation of the head or mechanism frame on a larger scale, with the case removed, clearly exposing the mechanism. Fig. 3 is a vertical section of Fig. 2 on the line *x*-*x*, looking in the direction of the arrow; and Fig. 4 is a sectional plan on lines *o*-*o* of Fig. 2. Figs. 5, 6, and 7 show, on an enlarged scale, the duplex clutch mechanism in which my improvement chiefly lies.

I will now state at the outset that the lamp in which I have shown my present invention embodied is, as may be observed, of a well-known type, in which the motive power consists, on the one hand, in the attraction of the magnets in the circuit of the lamp, and on the other hand the weight of the carbon-holders. The lamp is also of that type in which the armature-lever of the magnets carries a train of wheels which mesh at the leading pinion with rack-teeth on the carbon-holder, while the terminal spindle of the train is provided with an escapement and with a detent or scape wheel so arranged that when the magnetic attraction preponderates the wheel-train and carbon-holder are raised and the detent-wheel forced against a stop-tooth, which holds the train and prevents the descent of the carbon-holder; but when the attraction weakens and allows the armature-lever to retract slightly the detent is withdrawn and the wheel-train released to allow the carbon-holder to descend,

which is again stopped by the swaying of the armature-lever and the detention of the train when the carbon has "fed" sufficiently, as will be understood. It is therefore proper to state 5 that while I prefer this type of mechanism, yet my improvement is not confined thereto, and may be used with any suitable form of motor or regulating mechanism.

Now, the lamp here shown is, with the exception of my improvement, substantially identical with that set forth in my pending application, filed February 4, 1881, No. 25,403, and, as shown in the drawings, the mechanism is included between two fixed circular 15 heads, *a* *a'*, joined rigidly by the standards *b* *b'* and rod *b'*, and the whole effectually inclosed and protected when in use by a removable cylindrical ease, *c*. On the upper head, *a*, are fixed the binding-posts, to which the circuit 20 wires connect, as shown, and from the lower head, *a'*, arms *a''* extend and connect with pendent rods *d* *d'*, which are fixed at their lower ends to the cross-bar *e*, thus forming the harp of the lamp, in which the carbons appear 25 and which supports the globe and shade which inclose them. The globe and shade are not shown; but the former is supported on the circular depressed center of the cross-bar *e*, and the latter is suspended by the pendent 30 loops *f*. From the center of the cross-bar *e* arises a double holder, *g*, in which the two lower and negative carbons are clamped, as shown, while the upper and positive carbons 35 hang in line therewith from the upper regulated holders, *h* *h'*. These holders have the usual form of a long rod or tube, and pass through the mechanism frame, engaging with the mechanism therein, and are inclosed at their upper ends by long tubes *h''* *h'''*, which are 40 screwed into the upper head, *a*, and capped by the tip *i*. This tip is formed with two sockets, which fit onto the top of the tubes and are fixed thereon by set-screws and it has a central loop or eye, *j*, by which the whole 45 lamp may be conveniently suspended, and which forms at the same time a neat finial, rendering the structure symmetrical.

The carbon-holders *h* *h'* are placed at a convenient distance apart, as shown, and, as will 50 be observed from Figs. 2 and 3, are placed centrally in the lamp, or rather on its diametrical line equidistant on either side of the center, and on one side of them are arranged the motor-magnets *k* *k'* of the lamp. These magnets are of the kind now generally employed—that is, consist of two pairs of solenoids or axial magnets, one pair, *k*, being fixed to the lower head, *a'*, and the other pair, *k'*, being fixed to upper head, *a*, and the two facing each other, 55 so with a double armature or core, *l*, of an **H** form, such as claimed in my pending application, arranged to play between them. This **H**-core is connected by trunnions at its neutral center or cross-piece to the armature-lever *m*, 60 which lever, as shown best in Fig. 4, has the form of a light open frame of **T** shape placed

in horizontal plane, with its stem passing between the standards *b* *b'*, and there pivoted near the end of the stem on the trunnion-screws *m'*, which work through the standards and are 70 held by jam-nuts, as illustrated. The open panel in the head of this **T**-shaped lever-frame incloses the **H** armature or core, as seen in Figs. 4 and 2, in which it is trunnioned at a point above its center of gravity, so that the core 75 tends to hang vertical in the tubes of the solenoids.

In the open panel on the stem of the **T**-shaped lever is arranged the frame *n*, which carries the wheel-train, as shown; and this 80 frame is pivoted to the lever on the screws *n'*, near its outer end, at the lower and outer corner of the wheel-frame, as shown well in Figs. 2 and 4. The leading spindle *o* of this wheel-train is provided with pinions *o'* *o''*, which 85 mesh with the rack-teeth on the respective carbon-holders *h* *h'*, as seen best in Figs. 3 and 4, and on the middle of spindle is fixed the large or leading gear-wheel *f'*, which meshes with the succeeding pinion of the train, while 90 on the terminal spindle of the train is fixed the detent-wheel *p* and the escapement-wheel *p'*, engaged by the vibrating fly-escapement *p''*, which acts the part of a pendulum to prevent the too rapid motion of the train when released. 95

Now, *r* is a spring, fixed at its inner end to a projection extending down from the upper head, *a*, and at its outer end is securely clamped to the upper and outer corner of the gear-frame *n*, so that this spring thus acts as a parallel-motion link and causes the frame and its train 100 of wheels to always move up or down in a straight line with the carbon-holder when the armature-lever is swayed one way or the other, 105 as will be understood, and as shown in my pending application.

Now, referring to Fig. 2, the lower magnets, *k*, of the lamp, as will be understood, are of low resistance and situated in the direct arc-circuit, while the upper magnets, *k'*, are of high resistance and situated in a shunt, and these are so proportioned to each other that when the separation of the carbon points is normal, the attraction of the upper magnet, *k'*, 110 together with the pull of the adjustable tension-spring *s*, which act together, but antagonistic to the larger magnet *k*, is just sufficient to keep the armature-lever in its median position, as shown in Fig. 2, in which position the gear-frame will be raised sufficiently to bring its detent-wheel *p* into contact with a stop-tooth, *r'*, projecting from the spring *r*, thus holding the train, and thereby keeping the carbon-holder in suspension. When, however, the carbons 115 burn off so as to appreciably increase the length and resistance of the arc, the upper and shunt magnet, *k'*, preponderates over the direct magnet *k*, and, raising the core *l* and swaying the lever *m*, causes the wheel-frame *n*, and with 120 it the carbon-holder, to be depressed slightly, so as to decrease the separation of the points, 125 130

and if this depression is sufficient the detent-wheel will be withdrawn from the stop-tooth r' , thus allowing the train to escape and the carbon-holder to descend to give the necessary 5 "feed" at the arc. When the carbon-holder has thus descended sufficiently the magnet k at once preponderates over both the magnet k' and the spring s , and in pulling down the core l sways the armature-lever in the opposite direction, raises the gear-train, and brings the 10 detent in contact with the stop-tooth r' , thus stopping the train. When the train is thus stopped the carbon-holder becomes positively engaged with the armature-lever, and if the 15 current strength in the circuit increases or decreases slightly, or if the resistance of the arc increases or decreases slightly, the core l , armature-lever m , and with them the wheel, train, and carbon-holder, will bodily vibrate 20 up or down slightly, to correspondingly regulate the arc without releasing the train, as will be readily understood.

It will now be seen that the general mechanism of the lamp, so far as described, is substantially of the ordinary type, and is similar to that set forth in my pending application before referred to.

Now, the location of my present improvement is mainly at and on the leading spindle 30 o of the wheel-train, which forms in effect the driving device or connection between the motor-magnets and the carbon-holders; and attention may now be especially directed to this part, which is shown clearly in Figs. 3 and 4, 35 and in enlarged detail in Figs. 5, 6, and 7. This spindle, as will be observed, is about twice as long as that used in a single carbon-lamp, and is journaled at each end in elbowed extensions on the wheel-frame n , as seen in 40 Figs. 3 and 4.

On each end of the spindle are mounted the pinions $o' o''$, which mesh with the respective carbon-holders $h h'$, the right holder, h , (see Figs. 1 and 3,) being the leading holder, which 45 is shown near the end of its stroke with the carbons nearly exhausted, while the left holder, h' , is the succeeding one, controlling a fresh pair of carbons, and shown at the top of its stroke and out of action. This holder h' is not 50 only raised to the top of its stroke, but is there supported by a latch-lever, t , on the under side of the upper head, a' , as well shown in Fig. 3, its long arm being raised by a spring, t' , to hold its short arm in engagement with a 55 tooth, t'' , on the carbon-holder, which thus retains the carbon-holder in suspension. It will hence be understood that while the rack of each carbon-holder is always in engagement with its respective pinion $o' o''$, yet the leading carbon-holder is in active engagement with its pinion, and its weight is supported thereby, while the weight of the succeeding holder, h' , is relieved from its pinion and its engagement therewith is idle, as will further appear. 60 Now, the pinions are engaged with the spindle by the ratchet device heretofore em- 65 ployed—that is, the pinion o' is loose on the spindle, but has a ratcheted hub, u , which engages with pawls w on a disk, v , which is keyed with the spindle, so that the slip of the 70 pawls and ratchets allows the carbon-holder to be raised to any point without turning the train of wheels, (see Figs. 2 and 6,) yet these ratchets and pawls engage in the opposite direction and keep the holder positively engaged 75 with the gearing in its downward direction. In my lamp, therefore, the pinion of each carbon-holder is engaged with the driving-spindle in this well-known manner, the ratchets of both having the same direction, but a peculiar 80 result follows from this duplex arrangement, as will now appear. Thus: We will now consider that the armature-lever has been swayed so as to depress the gear-frame and release the train and allow the carbon-holder to descend 85 for feed. The weight of the holder in thus descending will turn the pinion o' in a direction to engage its ratchet with its pawl-disk u , and thereby turn the spindle o and the entire wheel-train, and through this spindle the opposite 90 pawl-disk, v' , which is keyed thereto, will of course also turn therewith; but, as will be readily observed, this pawl-disk will turn around the ratchet of the opposite pinion, o'' , 95 in its direction of slip, for of course the direction in which the driving-ratchet u engages is the same direction in which the driven pawl-disk v will slip, so that, hence, the second pinion, o'' , remains stationary in the rack of the 100 stationary carbon-holder h' , while the spindle turns loosely in it. Hence, by this plan of engaging the two carbon-holders with the same driving device through the intervention of clutches which bite in one direction and slip in the other and have the same direction of 105 engagement, it follows that, if the strain of one carbon-holder is borne by the mechanism at one clutch and the strain of the other relieved from it at the other clutch, the borne 110 one will be acted upon by the mechanism and perform all the necessary regulating movements in the ordinary way, yet these motions or actions will not react in the least on the other holder; hence by this very simple device I form a greatly-improved duplex lamp 115 in which the magnets and mechanism act on one carbon-holder at a time, and perform no greater work and require no greater strength than is the case with the single-carbon lamp. Now, in addition to this feature of the duplex 120 clutches, the device contains another peculiarity different from the mechanism of the single lamp—that is, the pawl-disks $v v'$, instead of being keyed immovably to the spindle o , are keyed with a certain amount of play. 125 Thus in Figs. 3, 4, 5, 6, and 7 it will be seen that pins $w w'$ are driven diametrically through the spindle and engage with short slots or notches on each side of the hubs of the pawl-disks, thus allowing a certain play between 130 the spindle and the disks. Now, we have been before considering the down or feed mo-

tion of the active carbon-holder and the rotation of the wheel-train under its impulse, which motions, as we have seen, are not communicated to the idle carbon-holder; but, in 5 addition to these motions, there are the bodily vibrations up or down of the entire wheel-train, and with it the carbon-holder when the rotation of the train is stopped by the detent-wheel, which motions for separation and 10 regulation must not, of course, be communicated to the idle holder any more than the rotary motion. In other words, it will be readily understood that when the wheel-frame is raised sufficiently high to catch the detent the 15 rotation of the train is stopped, and as the pinion o' can, hence, not turn on the rack of the holder h , the result is that the carbon-holder becomes bodily raised by any further rise of the train. Now, as the idle holder h' is stationary, it follows that when the wheel-train is 20 thus raised the pinion o'' must be free to roll on it in this upward direction, which is the direction in which its ratchets engage, and this idle-roll is allowed by the play just mentioned, as will be readily understood by again referring to Figs. 3 and 4. Thus it will be seen in these figures that the two pins $w w'$ in the driving-spindle o will always be at relatively opposite sides of their play in the slot- 25 ted hubs of the pawl-disks $v v'$ at the time when the rotation of the gear-train is stopped by the rise of the same against the stop-tooth, for the direction of the rotating strain on the spindle is of course such that the pawl-disk v is the driver and the disk v' the driven. Now, if the gear-train rises higher after its 30 rotation is thus stopped, it will of course lift the active carbon-holder h bodily with it, for all the play of the leading pin w is of course taken up; but during this upward bodily motion the opposite pinion, o'' , will roll idly in a 35 backward direction on the rack of the stationary holder h' , as the play in the slot of its pawl-disk v' is just in that direction which allows 40 of this backward idle-roll, being the same direction in which the ratchets engage, as will be understood, thus preventing the bodily up or down motion of the train being communicated to the stationary holder. This play 45 is therefore proportionately equal to the stroke of the armature-lever, and while it is always taken up at the active clutch, it is always free at the idle clutch to allow the idle backward roll of the pinion o'' on the stationary holder, 50 as just described, and well shown in Fig. 3. Hence by the constructions described neither is the rotary motion of the train when impelled by the descent of the active holder, nor is the bodily up-and-down motion of the train and 55 the active holder transmitted at all to the idle holder, which remains entirely stationary, unaffected and unborne by the mechanism, thus presenting a striking and valuable feature of my lamp, and accomplished by very simple 60 mechanism. Now, as soon as the carbons of the active and leading holder become nearly

exhausted a projecting pin, x , on the upper end of the active carbon-holder approaches the end of the latch-lever t , and, finally descending against the same, trips the latch and 70 allows the weight of the succeeding holder h' to fall into active engagement with its pinion o'' , while at the same instant a shoulder on the tip of the leading holder h becomes seated on the lamp-head a , thus relieving the weight 75 of the exhausted carbon-holder from the mechanism, and simultaneously transferring the weight of the fresh succeeding holder h' thereto. At the same instant the arc is formed between the fresh carbons, and the light is continued thereby without any perceptible break, for the transfer occurs, of course, with electrical quickness, and almost before the arc ceases at the exhausted carbons it is established at the fresh ones. Now, when this change occurs 80 the second holder, h' , becomes, of course, the active one and the first holder, h , is idle; but the action is precisely the same as already described, only reversed as concerns the two holders, for the holder h' will now go through 85 all the usual regulating movements without at all affecting the now idle holder h , as will be readily understood. It will hence be seen that any successive number of holders might be arranged in the same manner in one lamp 90 or apparatus, and each would come into action successively as the preceding one became exhausted. All those whose weight was relieved 95 from the mechanism, as described, whether exhausted or fresh ones, would neither be acted 100 upon by the mechanism nor react thereon.

I do not of course limit myself to the special mechanical parts illustrated, as already intimated, for of course any suitable species of clutch besides the ratchet and pawl, whether frictional or positive, may be used, and any suitable means for connecting the duplex clutches with the driving mechanism of the lamp and with the carbons or carbon-holders may be employed in lieu of the rotary wheel 110 train and the rack and pinions shown.

Another and minor novel feature of my lamp consists in the secondary spring, y , additional to and in combination with the adjustable tension-spring s . Both of these springs tend, of course, to pull down the carbon-holder in opposition to the main separating-magnet and in conjunction with the feed-magnet h' , and thus always serve to bring the carbons together, so as to insure the formation of the arc, 115 the parts being proportioned as follows: When the lamp is quiescent, with no current flowing, the parts tend to assume the median position shown in Fig. 2, the armature-lever being horizontal, in which position the weight of the core 120 and of the long arm of the armature-lever is just balanced by the weight of the short arm and the weight of the carbon-holder and that of the wheel-train, together with the tension of the secondary spiral spring y , so that the 125 gear-train is thereby raised toward the stop-tooth r' , but with hardly any pressure, so that

if the carbons happen to be separated the slightest additional strain will cause the gear-frame to be depressed and released, allowing the carbons to feed. This additional strain will be provided as soon as the lamp is put in circuit by the current, however weak, which will at once circulate in the shunt-magnet k' , and whose attraction will at once pull down the gear-frame, so as to release the same and allow the carbons to come together to form the arc, after which the main magnet k becomes energetic and moves the parts in the opposite direction, separating the carbons to form the arc, and lifting and stopping the wheel-train; hence, with the assistance of the spring y , without the spring s , the lamp is always fit for action, and this spring y is designed to be permanent and non-detachable, while the adjustable spring s is designed to be detachable for the purpose of adjustment, so that in case this adjustable spring should be left inadvertently detached when the lamp is put in circuit the lamp will yet be fully operative.

The spring s is adjusted as claimed in my application before referred to—that is, it is connected to its non-rotating adjusting-screw s' by means of an inclined pin, s'' , which meshes with its spirals, so that by detaching the hooked end of the spring from its armature-lever and turning the spring one way or the other it will be screwed in or out, and its active length thus increased or decreased, so as to correspondingly alter its elasticity, which adjustment, together with the adjustment of its screw, will enable any desired tension to be put upon the spring. Now, this tension is mainly to offset the excessive strength of the magnet k and to adjust the action of the lamp to the strength of current operating it, and to also enable the length of arc to be regulated as required, and made uniform when a number of lamps are placed in the same circuit, its function being thus distinct from that of the permanent spring y , which I term the "safety" or "balancing" spring.

The direction of the current through the lamp is as follows: Entering at the positive post on the head of the lamp, the current descends through the metal frame and through the upper carbon holder and carbon to the lower carbon, and thence flows upward through the rod d , which is insulated from the upper frame, but connects with the positive end of the coils of main magnet k , (see Figs. 1 and 3,) so that the current thence continues through the magnet k , and flows off by the negative insulated post on the head a , with which the negative end of the coils connect, as seen in Fig. 3. The opposite ends of the coils of the magnet k' connect directly to the respective binding-posts, as shown in Fig. 3, being thus in a shunt, as before stated.

I am aware that a duplex electric lamp has been heretofore proposed in which one carbon-holder was held off the motor mechanism by a catch while the leading one was in action,

and the leading one at its terminal movement released the second and allowed it to fall upon the motor mechanism, such as shown in Patent No. 233,399. In this case, however, the construction is quite distinct from mine, for the carbon-holders are engaged by intermittent ratchet-clutches which are sustained from or on the fixed frame of the lamp, whereas in my case the ratchet-clutches are sustained constantly on the motor mechanism; and in my case the ratchet-clutches are constantly connected with the carbon-holders, and with the motor mechanism, whereas in the other case the ratchet-clutches are disconnected from the motor mechanism; and, furthermore, in my case one carbon is actuated by the mechanism simply by being borne thereby, and the other is unaffected simply by being supported independently of its clutch without ever becoming disconnected from its clutch or the clutch from the mechanism, whereas in the other case one carbon is held out of action by holding its clutch entirely off the motor mechanism and the other is put in action by dropping its clutch onto the motor mechanism.

I do not broadly claim an electric lamp with two sets of electrodes, each connected with a single-motor mechanism and gear-train by ratchet-clutches sustained on said mechanisms, with a catch to hold the succeeding electrode from advancing while the leading electrode is in action; but I wish to here remark that my lamp is the only one of this class of which I am aware in which the succeeding electrode is supported entirely independent of its clutch or motor mechanism while the leading electrode endures, so that the mechanism lifts and supports only the electrode which is in action, and does not move or support the idle electrode, whereas the active electrode on its terminal motion removes its own pressure from the mechanism and transfers the pressure of the succeeding electrode thereto.

What I claim, therefore, as my invention is as follows:

1. A duplex electric lamp constructed with two or more sets of illuminating electrodes and a common motor or regulating mechanism connected constantly with each of said electrodes by ratchet or equivalent clutches having the same direction of action and slip sustained on said mechanism, and having an idle play in their connection with the mechanism equal to the maximum stroke of the mechanism, or nearly so, one of said electrodes being temporarily unborne and unaffected by the mechanism, and the other borne and actuated thereby and adapted on its terminal motion to remove its own pressure from the mechanism and transfer the pressure of the other electrode thereto, substantially as and for the purpose set forth.

2. In a duplex electric lamp, the combination, with two or more successively-acting electrodes constantly engaged with a common motor mechanism by ratchet-clutches sus-

tained on said mechanism, of a fixed supporting catch or latch adapted to directly engage and support the succeeding one of said electrodes independently of its clutch, and a device connected with the leading electrode which trips said catch at the terminal motion of the leading electrode and allows the pressure of the succeeding electrode to fall upon its clutch, substantially as and for the purpose herein shown and described.

3. In a duplex electric lamp, the combination, with two or more successively-acting electrodes constantly connected with a common motor mechanism by ratchet-clutches sustained on said mechanism, of a projection, t'' , on the succeeding one of said electrodes, and a fixed catch, t , to engage therewith, together with a projection, x , on the leading electrode,

adapted to trip said catch and release the succeeding electrode therefrom at the terminal motion of said leading electrode, substantially as and for the purpose set forth.

4. The combination, in an electric lamp, with a magnet in circuit with the source supplying the lamp and arranged to regulate the position of the carbons, and with an adjustable and detachable retracting-spring to antagonize the action of the magnet, of the additional safety or balancing spring y , designed to be constant or non-detachable, substantially as and for the purpose set forth.

JAMES J. WOOD.
